US00D705161S

(12) **United States Design Patent**
Chen et al.

(10) **Patent No.:** US D705,161 S
(45) **Date of Patent:** ** May 20, 2014

(54) **WATERPROOF CASING FOR ELECTRONIC DEVICE**

(71) Applicant: **Sinpro Electronics Co., Ltd.**, Pingtung (TW)

(72) Inventors: **Chih-Ming Chen**, Pingtung (TW); **Chinkuo Hu**, Pingtung (TW); **Hui-Ling Hsieh**, Pingtung (TW); **Han-Liang Li**, Pingtung (TW)

(73) Assignee: **Sinpro Electronics Co., Ltd.**, Pingtung (TW)

(**) Term: **14 Years**

(21) Appl. No.: **29/434,030**

(22) Filed: **Oct. 9, 2012**

(51) **LOC (10) Cl.** 13-03
(52) **U.S. Cl.**
USPC D13/110

CLAIM

The ornamental design for a waterproof casing for electronic device, as shown.

DESCRIPTION

FIG. 1 is a perspective view of a waterproof casing for electronic device, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.
